UNITED STATES PATENT OFFICE.

FRITZ B. ERNST, OF CHICAGO, ILLINOIS.

CAREY-IRON ARRANGEMENT.

Application filed January 24, 1921. Serial No. 439,540.

To all whom it may concern:

Be it known that I, FRITZ B. ERNST, a citizen of the United States, residing at Chicago, in the county of Cook and State of Illinois, have invented certain new and useful Improvements in Carry-Iron Arrangements, of which the following is a specification.

This invention relates to a new and improved carry iron arrangement for railway cars or more specifically to a particular form of striking casting and associated carry iron and their means of interengagement.

Carry irons are usually provided as separate members from the striking castings in order that they may be removed to facilitate removal of the draft rigging or associated parts. The carry irons are also subject to wear and ordinarily require replacement before the striking castings and hence should be separate elements. Heretofore carry irons have generally been retained in association with the striking casting by means of screws, bolts, cotter pins, or similar small parts which are subject to breakage, or which may work loose. The use of these small parts renders the carry irons unsafe since it may come loose and work out of place and drop the draw bar and coupler. Certain other carry irons have been designed with integral lugs adapted normally to engage portions of the striking casting. These carry irons, however, may become disengaged from the striking casting under rough usage where the car is jolted or jerked. They are therefore fundamentally unsafe.

It is an object of the present invention to provide a new and improved striking casting and carry iron assembly which is simple in construction and which avoids the use of any small connecting or retaining members. It is also an object to provide a structure of the character described which is simple in design and may be readily manufactured by the usual casting process. Other and further objects will appear as the description proceeds.

I have illustrated certain preferred embodiments of my invention in the accompanying drawings in which—

Figure 1 is a face view of a striking casting and carry device made according to my invention;

Figure 2 is a plan view of the device of Figure 1;

Figure 3 is an end view of the device of Figure 1;

Figure 4 is a section taken on line 4—4 of Figure 2;

Figure 5 is a face view showing a modified form of the device;

Figure 6 is a plan view of the device shown in Figure 5, a portion being broken away to better illustrate the construction;

Figure 7 is an end view of the device of Figure 5;

Figure 8 is a section taken on line 8—8 of Figure 6;

Figure 9 is a face view of a further modification of the device;

Figure 10 is a plan view of the form of the device shown in Figure 9;

Figure 11 is an end view of the form of the device shown in Figure 9; and,

Figure 12 is a section taken on line 12—12 of Figure 10.

The form of the device shown in Figures 1 to 4 comprises the striking casting 14 having the depending arms 15 adapted to receive between them the draw bar or coupler shank 16. This draw bar rests on the carry iron 17, the ends of which are supported by the cross portions 18 of the depending arms 15. As best shown in Figure 4, the arms 15 are provided with the slots 19 above the cross pieces 18. These slots are slightly greater in depth than the depth of the carry iron 17 and its depending lugs 20, which latter normally engage the inner faces of the cross members 18. It is to be noted that the depth of the lugs 20 is greater than the clearance 21 between the upper face of the draw bar 16 and the striking casting 14.

The form of the device shown in the figures from 5 to 8 inclusive comprises the striking casting 30 having depending arms 31. The draw bar 32 passes between these irons and rests upon the carry iron 33. As best shown in Figures 6 and 8, the carry iron extends upwardly at its ends, each end being provided with a T-head 34 which head fits into a socket in the lower end of the depending arm 31. The lugs 35 engage the rear faces of the T-head 34 and the openings 36 are provided in the rear of the lugs 35; the openings being of sufficient size to permit passage of the heads 34, and the space between the lugs 35 permitting passage of the portion of the carry iron below the heads 34. It should be noted that the height of the

lugs 35 is greater than the clearance 37 between the upper face of the draw bar and the adjacent surface of the striking casting. Obviously if desired the arrangement of the

5 engaging lugs may be reversed to permit withdrawal of the carry iron from the front.

The form of the device shown in the figures from 9 to 12 comprises the striking casting 41 having the depending arms 42 each 10 provided with the lateral opening 43 and with the upwardly extending inner lip 44. The carry iron 45 has downwardly extending ends 46 fitting in behind the lips 44. The carry iron supports the draw bar 47. The

15 lateral openings 43 in the arms 42 are of sufficient size to permit the endwise application and withdrawal of the carry iron. It is to be noted, however, that the distance which it is necessary to raise the carry iron

20 45 to permit it to be withdrawn through either opening 43 is greater than the clearance 48 between the upper face of the draw bar and the adjacent surface of the striking casting.

25 All forms of the device have the common characteristic that the carry iron is retained in place in the striking casting by the interengaging portions on these two elements which may be readily disengaged. The movement necessary for this disengagement, however, is greater than the clearance afforded between the draw bar and these parts. It is therefore impossible while the draw bar is in place for the carry iron to become accidentally disengaged from the striking casting, regardless of the rough treatment which it may receive in use. It is to be understood that the size of the coupler shank in the vertical direction is standardized at six inches 30 by the M. C. B. specifications, and it is therefore possible to construct my device with definite clearances.

40 In the form shown in Figure 1, with the draw bar removed, the carry iron is simply 45 lifted sufficiently for the lugs 20 to clear the cross pieces and it may then be removed through either opening 19, or tilted and removed from the bottom.

45 In the form shown in the Figures from 5 to 8, with the draw bar removed, the carry iron is lifted sufficiently for the T-heads 34 to clear the lugs 35. It is then moved rearwardly beyond these lugs and drawn downwardly out of the casting. It is replaced in 55 the reverse manner.

In the form shown in the Figures 9 to 12 the draw bar may be raised and removed through either lateral opening 43.

60 It is thus seen that I have designed a carry iron arrangement such that the carry iron is positively retained in place so long as the coupler shank or draw bar is in place. Accidental or malicious removal of the carry iron is therefore prevented. It has no small 65 retaining elements which may work loose or

be removed. The device is extremely simple in construction and may be readily manufactured and is adapted for easy use.

While I have described more or less precisely the details of construction of my invention, I do not wish to be understood as limiting myself thereto, as I contemplate changes in form and the proportion of parts and substitution of equivalents as circumstances may suggest or render expedient, 70 without departing from the spirit of my invention. 75

I claim:

1. A striking casting having depending arms adapted to receive a carry iron, a carry 80 iron retained therein, a draw bar supported by the carry iron and having a predetermined vertical clearance from the striking casting, and interengaging lugs upon the ends of the carry iron and the casting arms, 85 the interengaging portions of the carry iron and casting being greater in extent than the draw bar clearance.

2. A striking casting having depending arms adapted to receive a carry iron, a carry 90 iron retained therein, a draw bar supported by the carry iron and having a predetermined vertical clearance from the striking casting, and interengaging lugs upon the ends of the carry iron and the casting arms, 95 the interengaging portions of the carry iron and casting being greater in extent than the draw bar clearance, the depending arms of the striking casting being provided with inwardly extending flanges preventing forward or rearward movement of the carry iron when in any vertical position. 100

3. A striking casting having depending arms adapted to receive a carry iron, a carry 105 iron retained therein, a draw bar supported by the carry iron and having a predetermined vertical clearance from the striking casting, and interengaging lugs upon the ends of the carry iron and the casting arms, 110 the interengaging portions of the carry iron and casting being greater in extent than the draw bar clearance, the depending arms of the striking casting being provided with inwardly extending flanges preventing forward or rearward movement of the carry iron when in any vertical position, and being provided with lateral openings adapted to 115 permit the lateral withdrawal of the carry iron when raised to disengage the coating lugs upon the carry iron and striking casting. 120

4. A striking casting having depending arms adapted to receive a carry iron, a carry 125 iron retained therein, a draw bar supported by the carry iron and having a predetermined vertical clearance from the striking casting, the depending arms being provided with inwardly and upwardly extending flanges at their lower end and the carry iron being provided with downwardly extending 130

flanges adapted to engage the arm flanges, the coacting portions of the flanges being greater in height than the draw bar clearance.

5 5. A striking casting having depending arms adapted to receive a carry iron, a carry iron retained therein, a draw bar supported by the carry iron and having a predetermined vertical clearance from the striking 10 casting, the depending arms being provided with inwardly and upwardly extending flanges at their lower end and the carry iron

being provided with downwardly extending flanges adapted to engage the arm flanges, the coacting portions of the flanges being greater in height than the draw bar clearance, and the depending arms being provided with openings adapted to permit the withdrawal of the carry iron when raised to disengage the coacting flanges upon the arms 15 and carry iron.

Signed at Chicago, Illinois, this 19th day of January, 1921.

FRITZ B. ERNST.
